CATAMENIAL SACK

Edward J. De Ville, Halethorpe, Md.

Application March 31, 1934, Serial No. 718,470

2 Claims. (Cl. 128—290)

This invention relates to sanitary pad shields generally. More particularly this invention relates to a sanitary pad shield adapted to be supported upon the underside of the pad, while in use, and prevent objects, particularly wearing apparel, from coming in contact with the pad.

An object of this invention is to provide a sanitary pad shield made from a piece of flexible and pliable material and having strips or bands extending across sections of the pad in such a manner that the pad and shield are effectively held together in use, yet may be easily, without extensive handling, separated after use.

Another object of this invention is to provide a sanitary pad shield of flexible and pliable material adapted for use on the underside of a sanitary pad as a guard, the shield being so shaped that sections of the pad extend over the edges thereof and prevent rubbing contact between surfaces of the shield and the skin of the user.

Other and further objects of this invention will be apparent to those skilled in the art to which it relates from the following specifications and the appended claims.

In accordance with this invention I provide a sanitary pad shield of flexible and pliable material, such as sheet rubber, adapted to be worn on the under or exposed side of the pad. Elongated strips are cut from the longitudinal edges of the shield and folded over and upon the body of the shield, forming loops with portions of the body, for the purpose of encircling or surrounding sections of the pad being used therewith and holding the pad and shield together, during use.

Details of construction will be more clearly apparent from the following specification and the drawing in which, briefly, Fig. 1 illustrates the blank, with the cuts and folding lines, showing the manner in which the preferred form of the shield of my invention is cut and formed prior to assembly. Fig. 2 shows an embodiment of the preferred form of this invention assembled together with a pad. Fig. 3 is a side elevation. Fig. 4 illustrates a modified form of the invention; and Fig. 5 shows the manner in which the shield shown in Fig. 4 is assembled.

Referring to the drawing in detail, reference numeral 1 designates the blank of pliable material, such as rubber or similar substance. The blank, 1, is made of substantially the same shape as the sanitary pad, with which it is to be used; however, it is preferred to make it of slightly greater width than said pad. This blank is cut substantially at the center thereof along lines 2 and 3, which extend from each of the longitudinal

edges of the blank inward a short distance toward the center of the blank. Incisions 4 and 7 extend parallel to the adjacent longitudinal edge of the blank in opposite directions from the cut 3. Likewise the cuts or incisions 5 and 6 extend in opposite directions from the cut 2, parallel to the adjacent edge of the blank. After these cuts are made, in any suitable and convenient way, either mechanically or by manually operated tools or devices, the strips 4a, 5a, 6a and 7a are folded along the lines 4b, 5b, 6b and 7b, respectively, to form sanitary pad gripping or encircling elements, as illustrated in Fig. 2, the free ends of these strips being attached to the body of the blank at 4c, 5c, 6c and 7c, respectively.

By cutting and folding these strips 4a, 5a, 6a and 7a from the sides of the blank, the sides of the finished unit are left indented and permit the shield to be used without rubbing irritation to the skin of the user. Furthermore, the use of the material removed from the sides of the blank permits the use of a substantially rectangular blank of minimum size, and in this way economy in raw material is effected, since the number of waste pieces cut away from the blank is kept at a minimum.

The portions 8, 9, 10 and 11 are cut away from the blank along lines 8a, 9a, 10a and 11a, respectively. The sanitary pad, 12, is positioned on the shield as illustrated in Figs. 2 and 3, with the strips 4a, 5a, 6a and 7a extending diagonally across the corner portions of the pad. The binding or supporting tapes 13 and 14 of the sanitary pad are threaded through the apertures formed between the pairs of straps 4a, 5a, and 6a, 7a, respectively. These pairs of straps may be vulcanized or cemented together at 15 and 16, where they cross.

In Figs. 4 and 5, a modified form of this invention is illustrated. In this embodiment of this invention the strips 17, 18, 19 and 20, cut from the sides of the body, are folded over the body toward the end thereof. The ends of these strips are cemented or vulcanized to the end edges of the shield body, as illustrated. Holes 21 and 22, for receiving the sanitary pad tapes, are formed in the ends of the shield body. These holes may be properly reinforced by suitable fabric vulcanized or molded into the body around the holes.

Other modifications of this invention may be made without departing from the spirit and scope thereof, and, therefore, while I have described this invention in detail, it is not desired to limit it to those details except in so far as they are defined by the following claims.

What I claim and desire to secure by Letters Patent of the United States is as follows:

1. A blank for a sanitary pad shield, comprising an elongated substantially rectangular piece of pliable material, having the corners thereof removed and having incisions extending adjacent to the longitudinal edges thereof and substantially throughout the length of said piece of material to form relatively narrow strips at the sides 5 of said blank, said strips each being cut substantially through the middle thereof to form free end strips adapted to be folded diagonally over the ends of said blank.

2. A blank for a sanitary pad shield, comprising an elongated substantially rectangular piece of pliable material, having the corners thereof removed and having incisions extending along the longitudinal edges thereof, said incisions being positioned substantially adjacent to said longitudinal edges to form relatively narrow free end strips at the sides of said blank, said strips each being of a length sufficient to extend diagonally across the ends of the said blank. 5 10

EDWARD J. DE VILLE.
